UNITED STATES PATENT OFFICE.

JAMES M. McCLELLON, OF EVERETT, MASSACHUSETTS.

LOCOMOTIVE-BOILER.

1,203,214.

Specification of Letters Patent. Patented Oct. 31, 1916.

Application filed December 23, 1912. Serial No. 738,127.

To all whom it may concern:

Be it known that I, JAMES M. McCLELLON, a citizen of the United States, residing at Everett, county of Middlesex, State of Massachusetts, have invented an Improvement in Locomotive-Boilers, of which the following description, in connection with the accompanying drawing, is a specification, like characters on the drawing representing like parts.

This invention relates to locomotive boilers and particularly to that type of locomotive boiler which embodies in its construction a condenser and means for forcing air through the condenser thereby to condense the exhaust steam therein and then delivering said air to the fire box, and simultaneously producing an induced draft through the flues from the fire box.

The object of the invention is to provide a novel locomotive boiler of this type having a novel arrangement of means for producing the forced and induced draft and wherein novel provision is made for both superheating the steam and heating the water of condensation which is returned from the condenser to the boiler.

The construction of my locomotive boiler is such that there will be no back pressure on the cylinders and consequently the engine will be capable of developing a much greater power than if such back pressure did exist; the operation of my novel induced and forced draft mechanism will permit of a better control of the fire, and, therefore, will increase the steaming qualities of the locomotive, and the arrangement for superheating the steam and heating the feed water is such as to make the operation of the locomotive extremely economical.

I will first describe some embodiments of my invention and then point out the novel features thereof in the appended claims.

Referring to the drawings wherein I have shown a selected embodiment of the invention for the purpose of illustrating the principle thereof, Figure 1 is a longitudinal sectional view through a locomotive boiler having my improvements applied thereto; Fig. 2 is a side view of a portion of the locomotive; Fig. 3 is a longitudinal sectional view through the front end of a boiler showing a modified arrangement of the forced and induced draft apparatus; Fig. 4 is an enlarged

section on the line $x-x$, Fig. 3; Fig. 5 is a view of the draft-regulating device for regulating the induced draft.

Referring first to Fig. 1, 1 designates the shell of a locomotive boiler which is formed at one end with the usual fire-box 2 and also with the smoke chamber 3 and the smoke stack 4. Situated in advance of the boiler and forming what amounts to a forward extension thereof is a condenser designated generally by 5. While it would be within the invention to use any condenser, that herein shown is similar to the condenser illustrated and described in my co-pending application Se. No. 415,826, filed February 14, 1908. This condenser comprises a steam-receiving chamber 6 into which the steam is delivered from the exhaust pipe 7 that connects with the engine cylinders, headers 8 which communicate with the steam-receiving chamber 6, and condensing pipes 9 which connect the headers 8 with other headers 10 in which the water of condensation is collected. This condenser is confined in a casing 11 which forms in effect a continuation of the boiler shell and which is open at its front end so that the air may be drawn in over the condenser pipes thereby condensing the steam therein. The water of condensation which collects in the headers 10 is returned to the boiler through the pipe 12. Inasmuch as this particular form of condenser forms no part of my present invention I have not deemed it necessary to further illustrate or describe it herein, especially as it is described and claimed in my said co-pending application. Situated within the smoke chamber 3 immediately in the rear of the condenser is a fan 14 which is constructed to draw the air through the condenser and deliver the air into a return pipe 15 which leads back to the ash-pan 70 of the fire-box. This fan 14 constitutes, therefore, a means for producing a forced draft and it also operates to force air currents across the condensing pipes 9. 16 is a draft-inducing fan also located within the smoke chamber, said fan operating to induce a draft through the flues 23 and to force the waste products of combustion out through the smoke stack 4.

My locomotive boiler is constructed so as to present not only a steam-generating compartment in which the steam is generated, but also a superheating compartment in

which the steam is superheated before it is delivered to the cylinder and a feed water heating compartment in which the feed water is heated. Further, my locomotive is 5 so constructed that the products of combustion which are taken from the fire-box pass through these compartments successively. I will preferably arrange the compartments so that the products of combustion 10 and hot gases pass directly from the fire-box through the steam-generating compartment, where they give up a certain portion of their heat in the generation of steam, and thence pass through the super- 15 heating compartment where they give up a further proportion of their heat in super-heating steam, and finally pass through the feed water heating compartment. While these different compartments can be pro- 20 duced in various ways, I have herein shown them as formed by partitions which extend diametrically across the boiler shell in a transverse direction. Said shell is provided with the transverse partitions 17 and 18 25 which form between them a superheating compartment 19 and which also divide the boiler into the steam-generating compartment 20 and the feed water heating compartment 21. This feed water heating compartment 30 is located between the superheating compartment 19 and the flue sheet 22. The steam-generating compartment 20 has therein the usual flues 23 through which the products of combustion pass from the smoke 35 box into the superheating compartment 19. The feed water heating compartment has therein a bank of flues 24 which extend through the flue sheets 18 and 22 and through which the products of combustion 40 pass from the superheating compartment to the smoke chamber. The products of combustion thus pass successively through the steam-generating compartment 20, super- 45 heating compartment 19 and feed water heating compartment 21. Situated within the superheating compartment 19 are a plurality of superheating tubes 26 arranged so that the steam passes through them as it is taken to the cylinder. While these super- 50 heating tubes may have any suitable shape, I have herein illustrated them as having a circular shape so that they correspond in shape to the shell 1. They are connected at their ends to a header 27 having a plurality of compartments, 71, 72, one end of 55 the tubes leading into one compartment 71 and the other leading into the other compartment 72.

The steam is delivered into one compartment 60 from the steam dome 28 through a steam pipe 29 and after passing through the tubes 26 and the various compartments, the superheated steam is delivered from the superheater through a pipe 30 which leads to the engine cylinders. This pipe 30 is

herein shown as extending through the feed water heating compartment 21, but is prevented from having contact with the water therein by the walls of an enlarged flue 31 through which the pipe 30 passes. 70

The fans 14 and 16 may be operated in any suitable way. As shown in Fig. 1 they are both driven from a prime mover situated within the smoke chamber 3, said prime mover being in the form of a steam turbine 75 32 which is operated by the steam generated in the boiler and may be controlled from the cab of the engine by any appropriate controlling means. The exhaust from the turbine is delivered through an exhaust 80 pipe 33 into the exhaust pipe 7 and thence into the chamber 6 of the condenser. The water of condensation which collects in the headers 10 of the condenser is delivered through the pipe 12 to a pump 34 which 85 pumps it into the feed water heating compartment 21 through a pipe 35. This pump can be operated in any suitable way, as by means of a steam turbine 36, the exhaust 90 from which is delivered to the exhaust pipe 7 through a pipe 37. The feed water heating compartment 22 is connected to the steam-generating compartment 20 through a pipe 38 which is connected to the top of the compartment 20 so that when water is pumped 95 into said compartment and the latter is filled, the water will overflow into the steam-generating compartment. 99

In Fig. 3 I have shown another embodiment of my invention wherein the motor for operating the fans 14 and 16 is located in front of the condenser instead of in the smoke chamber. Where this construction is employed it is possible to place the fans nearer together and thus make a smaller 100 smoke chamber. The motor 32 for operating the fans is shown as sustained in an extension 39 of the shell 11 of the condenser, and this motor is connected to the fans by means of a shaft 40 which extends centrally 105 through the condenser. I will preferably provide a shield or deflector 41 which is situated in front of the motor 32 and operates to deflect air currents around the latter. In order to get a more effective action in the 110 superheater I will preferably use a baffle plate 69 which is secured to the header 27 and depends therefrom, said baffle plate being of a size to fill the space within the inner tube 26. This baffle plate compels the hot 115 gases to pass around through the tubes 26 and thus insures a more perfect superheating action. I have also provided herein 120 means for regulating the induced and forced draft. The induced draft may be regulated either by controlling the speed of the fan 16 or by regulating the effective action thereof without varying its speed. The speed of the fan might be varied by varying the speed 125 of the engine 32 or by providing transmis- 130

sion gearing between the engine and the fan. The effective action of the fan may be varied by means of a damper which will admit air to the smoke chamber, thus reducing the suction therein and thereby reducing the induced draft. For this purpose I have shown a damper 68 in the side of the shell 1, said damper having an arm 67 connected thereto to which is connected a link 66 leading to the cab of the engine. This damper 68 controls air ports leading into the smoke chamber 3 and when the damper is turned into the dotted line position Fig. 5 the air ports are open. By opening or partially opening the air ports the suction in the smoke chamber 3 will be correspondingly reduced thereby reducing the induced draft. The forced draft can be controlled in various ways either by controlling the speed of the fan 14, or by providing a by-pass for the air. In Fig. 1 I have shown the pipe 15 as having an outlet 64 communicating therewith which is controlled by a damper 65. When the damper 65 is closed all the air delivered from the fan 14 will pass into the ash-pan 70 while if the damper 65 is open or partially open, a proportion of the air will be delivered through the outlet 64.

While I have shown herein some illustrated embodiments of the invention, I do not wish to be limited to the constructional details shown.

Having fully described my invention, what I claim as new and desire to secure by Letters Patent is:

1. In a locomotive boiler, the combination with a shell having a fire box at one end and divided to present a steam-generating compartment, and a feed water heating compartment, of means for conveying the products of combustion through said compartments successively, a condenser situated beyond the end of said shell and having provision for passing air currents therethrough, means to deliver the water of condensation accumulating in the condenser to the feed water heating compartment, means to induce a draft through the compartments successively, and means in the rear of the con-

denser to draw air therethrough and force it into the fire box.

2. In a locomotive boiler, the combination with a shell having a fire box at one end, of a steam generator, a superheater, a feed water heater, and an induced draft fan for drawing the products of combustion from the fire box through the steam generator, superheater and feed water heater, successively, all situated within the shell and arranged in the order named, a condenser in front of said shell, a combined suction and forced draft fan situated in the rear of the condenser and connected to the fire box and operating to draw air through said condenser and deliver it to the fire box, and means for operating said fans in such relation to each other as to preserve a proper pressure balance in the fire box.

3. In a locomotive boiler, the combination with a shell having a fire-box at one end, of a steam generator, a superheater, a feed water heater, an induced draft fan for drawing the products of combustion from the fire-box through the steam generator, superheater and feed water heater, successively, and a combined suction and forced draft fan, all situated within the shell and arranged in the order named, an open-ended condenser situated in front of the shell, a connection between said combined suction and forced draft fan and the fire box so that said fan will operate to draw air through the condenser and deliver it to the fire box, a steam turbine for operating both of said fans, a steam pump connected to the condenser and to the feed water heater to return the water of condensation to said feed water heater, the exhausts of said pump and turbine both being connected to the exhaust pipe of the locomotive.

In testimony whereof, I have signed my name to this specification, in the presence of two subscribing witnesses.

JAMES M. McCLELLON.
